UNITED STATES PATENT OFFICE

2,680,593

ESCAPE DEVICE

William D. McIntyre, Monroe, Mich.

Application February 7, 1950, Serial No. 142,857

4 Claims. (Cl. 254—151)

1

The present invention relates to safety devices and more particularly to a reel and tape or wire so arranged that a person may utilize the device to descend in safety from the exterior of a building or other structure.

Various attempts have been made to provide escape devices particularly for use as safety devices in the event of fire. Such devices have included ropes and reels mounted adjacent window openings and so arranged that the rope payed out from a reel located stationarily adjacent the window opening.

Thus, the rate of descent was not under the control of the user of the device in any way.

In the present invention the reel and cable are arranged in such manner that the reel is located adjacent the user of the safety device at all times during the descent and the rate of descent is automatically controlled by the weight of the user, as well as being, where desired, subject to his own manual control.

The primary object of this invention, therefore, is the provision of a novel escape device comprising a cable or tape and reel where the reel is located at all times adjacent the user of the cable or tape is controlled with respect to the rate of descent automatically by the weight of the user and wherein the user may, if he desires, exert additional braking pressure.

The foregoing and many other objects of the invention will become apparent in the following description and drawings in which:

Figure 1 is a view in perspective illustrating the use of the novel escape device of the present invention.

Figure 2 is a cross-sectional view taken on line 2—2 of Figure 3 looking in the direction of the arrows of the novel escape device utilizing a tape arrangement.

Figure 3 is a view partly in section taken from line 3—3 of Figure 2 looking in the direction of the arrows and showing a side view of the tape and reel.

Figure 4 is a view corresponding to that of Figure 3 showing, however, the automatic compensation of the brake as the tape pays out.

Figure 5 is a cross-sectional view taken on line 5—5 of Figure 6 looking in the direction of the arrows and illustrating the present invention as applied to the utilization of a cable.

Figure 6 is a side view partly broken away of the escape unit of Figure 5.

Figure 7 is a cross-sectional view taken on line 7—7 of Figure 6 looking in the direction of the arrows.

2

Figure 8 is a developed view of the supporting device attached to the escape device for the person utilizing the same.

Referring first to Figures 1 to 4, the novel escape device therein shown comprises a casing 10 having the flat side walls 11, 12 and the peripheral wall 13.

The peripheral wall 13 is provided with a slot or opening 14 and the ends of the peripheral wall 13 at the slot or opening 14 are curled over to provide the bearings 15, 15 for the tape 16 which emerges from the slot 14, the bearing elements 15 being appropriately curved so that no cutting stress or additional undesired frictional stress will be placed on the tape 16 as it emerges from the casing 10.

In use, the entire unit is arranged with the tape 16 completely wound in the casing 10 and a short length of the tape 16, approximately for instance ten feet, extends from the casing 10 so that the free end may readily be secured around some stationary object in the room, such as a water pipe, radiator pipe or an appropriate piece of heavy furniture, to provide an anchor for the tape 16.

Various means may be utilized to provide this securement. Thus, for instance, the tape 16 may be provided at its free end with a hook or buckle which will facilitate the securement of the tape around the stationary object or as shown in Figure 1 an auxiliary cable end 20 may be riveted at 21 to the end of tape 16, the cable end 20 being provided with a friction type buckle 22 generally well known so that an end of cable 20 may be wrapped around a pipe 23 and secured in buckle 22.

The tape 16 may be provided with a similar buckle so that the tape may be wound around a pipe 23 without the necessity for the additional cable end 20.

The casing 10 is provided with a central hollow bushing 30 which forms an axle for the reel 32 within the casing 10. The central portion 33 of reel 32 rotates on the bushing 30. Bushing 30 is provided with the annular flanges 35 which are turned over on the outer surfaces of the walls 11 and 12 of casing 10; the said walls 11 and 12 being provided with appropriate openings 36 and 37 to permit the mounting therein of the bushing.

The portions of walls 11 and 12 at openings 36 and 37 are turned in to form the inwardly directed annular flanges 40 and 41 spaced from the bushing 30. The base of reel 32 is provided with the annular flanges 43 and 44, respectively, 55 which are held rotatably between flanges 40 and

3

the bushing 30 on one side and 41 and the bushing 30 on the other side. This prevents any skewing of the reel base 33 which may interfere with the operation of the device.

The reel base 33 has secured thereto and preferably integral therewith the circular disc members 45 and 46 which define an annular space 50 in which the tape 16 may be wound, the space 50 being so dimensioned that the turns of the tape 16 wound therein are controlled and cannot slip laterally while, nevertheless, they may move freely with respect to the disc walls 45 and 46.

The outer ends of walls 45 and 46 are provided with the annular flanges 52, 53, respectively, these flanges also assisting in preventing skewing of the reel and primarily providing a brake drum on which the brake 60 may operate in a manner hereinafter described to control the rate of unwinding of the reel 32.

A bell crank lever 70 is rotatably mounted on the pivot 71 at the lower end of casing 10 between walls 11 and 12 and beneath the tape reel 32. The upwardly directed end 73 of bell crank lever 70 is provided with pin 74 around which the loop 75 of brake 60 is secured, loop 75 being maintained by the rivet 76.

The brake band 60 is slotted and held on one side by pin 74, the loop 75 on each side being held in place against arm 73 of the bell crank lever 70 by the side walls 11 and 12 of the housing.

The brake band is also slotted at the top to provide an exit for the tape as shown at 14 in Figure 13.

The two part brake band 60, 60 is wrapped around the flanges 53 and 52, respectively, each of which forms a brake drum for the brake band, and the end of the brake band is slotted and secured by loops 80 to pin 81 on arm 82 of bell crank lever 83 pivoted on pin 84 at the right side of the lower end of the casing 10 as shown in Figure 3.

The securing of the opposite ends of the brake band to the pin 81 of bell crank lever 83 is for compensating purposes to ensure steady brake pressure as hereinafter described.

Arm 90 of bell crank lever 70 is provided with means such as the opening 91 located above the slot 92 at the lower side of casing 10 in the peripheral wall 13 to which a cable 100 or other suitable means may be secured to support the individual using the device.

In the embodiment shown, cable 100 is connected to three straps 101, 102, 103. Strap 102 passes from the securing point 105 at the lower end of the short cable 100 through a cloth, canvas or other breeches buoy type of support 106 under the seat portion thereof and up once more continuously as strap 103 back to the point of securing.

In Figure 8 there is shown an arrangement wherein the straps 102 and 103 which are essentially a single strap are held in any suitable manner on the backing or breeches buoy type of device 106.

The front flap 110 of the support 106 is provided with strap 101 riveted thereto. The main section 106 is provided with waist bands 111 and 112, one of which has a buckle 113 and the other appropriate openings 114 so that the waist bands 111, 112 may be buckled around the waist of the user to hold him in the position shown in Figure 1 where he is free to brace his feet against the building wall during descent and where in the event of any disability he is fully supported so that he will be safe during descent should he be

4

unable to provide any assistance for himself during the descent.

It will be seen that the rate of paying out of tape 16 is controlled since the rate of rotation of reel 32 within casing 10 is in turn controlled by the brake band 60. Brake band 60 is tensioned by the downward pull on arm 90 exerted by the weight of the person descending. Arm 90 since it is part of the bell crank lever 70 exerts a clockwise force on arm 73 to tension the brake band.

The brake band 60 is provided with appropriate friction surfaces 120 to exert the required braking force. The degree of braking force is determined by the weight hanging from end 90 of the bell crank lever 70.

Thus, a lighter person will exert a lesser braking force and a heavier person will exert an increased braking force. Thus, the weight of the person using the device and the braking force exerted are proportional to each other so that a constant rate of descent is provided irrespective of the size of the person making the descent.

However, as the diameter of the outer turn of the tape in reel 32 decreases owing to the paying out of the tape, the distance of the tape from the center of rotation 30 decreases, thereby decreasing the moment of the tape around the center. Owing to this decrease in moment, the rotative force on the reel will gradually be decreased as the tape decreases in diameter from the condition of Figure 3 when the descent starts to the condition of Figure 4 where the descent is almost completed.

Unless special means were provided to compensate for this, the braking force, should it be maintained at a constant force, will tend to slow down the reel to a halt. This is avoided or rather compensated for by the utilization of the compensating bell crank lever 83 above described.

As previously pointed out, the opposite ends of the brake band were fastened to pin 81 on arm 82 of bell crank lever 83. The other arm 130 of bell crank lever 83 comprises a finger passing between the side walls 45 and 46 of the reel 32 and resting on the outer surface of the tape 16 on the reel 32.

As the diameter of the tape 16 on the reel 32 decreases, the pull of the brake band on pin 81 drives the finger 130 in against the outer surface 50 of the tape 16 remaining on reel 32. This permits pin 81 to move counterclockwise in a direction to loosen the brake band 60. The length of arm 82 of bell crank lever 83 is adjusted so that the degree of loosening of the brake band 60 as the tape unreels compensates exactly for the decrease in moment of the outer turn of the tape about the center axle 30 so that a constant rate of descent is maintained.

In addition, opening 94 is provided at the outer end of arm 90 of bell crank lever 70 and cable 95 is secured therein to serve as a hand-brake pull—the greater leverage permitting the individual using the device to stop his descent at any time by a pull on cable 95.

In actual use, therefore, the person desiring to utilize the escape device fastens the end 20 of the cable secured to tape 16 or the end of tape 16 around the stationary structure, such as the pipe 23. Enough of the tape, as previously pointed out, extends from the casing so that the individual may effect this securing and reach and climb out of a window before the braking device takes effect.

The individual after making the securing 75 steps into the canvas seat 106, which as previously

pointed out is constructed like a breeches buoy, buckles the waist bands 112 and 111 together around his waist.

He then drops down whereupon the brake band 60 is tensioned around the brake drums to a degree in proportion to his weight in order to slow down his rate of descent. The metallic tape 16 should not be too hard drawn so that the wrapping stress would be low.

It has been found that an appropriate tape for this purpose may be .022 thick by $\frac{1}{4}$ " wide drawn steel ribbon, S. A. E. 1085 or equivalent, wt.—.0193 #/foot, ultimate strength 825 pounds minimum, yield strength 745 pounds maximum with a spool diameter of 1.75" and 130 turns. The last turn will be 7.5" in diameter providing 157 feet of tape and thereby making the device usable up to approximately fifteen stories.

The casing and spool are preferably of an aluminum alloy and the brake chute of steel.

In Figures 5, 6 and 7 the invention is shown as applied to the utilization of a cable rather than a tape with a different type of braking action. The cable 216 is wound on the spool 232 which rotates within the anti-friction bushings 230.

The casing walls 200 and 201 are provided with central hubs 202 and 203, respectively, which may rotate freely on the outside of the anti-friction bronze bushings 230. A peripheral wall 213 is also provided having an opening 214 at its upper side through which the cable 216 may pass.

The opening may be appropriately curved as at 215 or provided with other bearing surfaces so that no binding or tearing force will be placed on the cable 216. The walls 200 and 201 are thus rotatable with respect to the reel 232 and vice versa.

Reel 232 is provided with the discs 210 and 211 serving to contain the cable 216 wound thereon. Walls 200 and 201 are provided with the annular brake linings 212 and 212a which engage the walls 210, 211 of the reel 232 to brake the same. Brake pin 250 passes through the center of reel 232 and has on one side a head 251 engaging the outer surface of wall 200 in hub 202. On the opposite side brake pin 250 passes through bearing 252 in hub 203 of wall 201.

Braking lever 260 is pivotally mounted on pin 261 which extends transversely through the braking pin 250. The lower end 262 of braking lever 260 extends down beneath the casing unit and terminates in appropriate means, such as the metal loop 263 to which the harness shown at the lower end of Figure 1 and in Figure 8 may be secured. The upper end 265 of braking lever 260 is provided with a cross piece 266 which bears against the outer surface of hub 203 of wall 201.

The weight of the person descending exerted on loop 263 at the end 262 of lever 260 exerts a counterclockwise rotative movement about pin 261 of the lever 260, driving section 266 of arm 265 of lever 260 against the outside of hub 203 of wall 201. Owing to the curvature of lever 260 at 276, portion 266 of lever 260 now becomes the fulcrum and the lever 260 exerts a pull toward the right on cross pin 250.

Thus, exactly equal and opposite forces are exerted, to the left by section 266 of the lever 260 and to the right by pin 261 on which the lever 260 is pivoted.

Therefore, hub 203 and wall 201 are driven to the left and hub 202 and wall 200 are pulled to the right, squeezing the braking surfaces 212a against the discs 210 and 211 of the reel 232.

The braking force exerted is thereby in pro-

75

portion to the weight of the person suspended from loop 263 of the lever.

The loop 263 of lever 260 is located beneath the opening 214 so that the unit will be erect during descent and not be skewed to one side. The unit is used in the same way as was described for Figures 1 to 4.

In addition, a manual braking control may be provided comprising the additional lever 280 also pivoted on pin 261 and having the arm 281 to which a metal loop 282 is secured and from which may hang the manual braking cord.

The opposite end of lever 280 is provided with the cam surface 285. When the cord attached to loop 282 is pulled, lever 280 rotates on pin 261 to cause the cam surface 285 to push wall 201 to the left and to cause pin 261 acting through pin 250 to pull wall 200 to the right.

The leverage is such that this additional braking force which may be manually exerted may bring the device to a stop. Thus, if the rate of descent is too fast or if there is any reason to stop the device, the user may do so by pulling on the free cord attached to the loop 282.

Initial braking force may be provided by the compression spring 290 between wall 201 and lever 260 so that the cable 216 may not be accidentally pulled out before it is intended to be used.

Also, to prevent undesired unreeling of cable 216, a lock pin 300 may be inserted through opening 301 in hub 202, opening 302 in the reel axle 232 and additional opening 303 in the hub 202.

Before the reel can rotate to permit the unwinding of cable 216, the pin 300 must first be drawn out. Where the compression spring 290 is used, then to maintain some initial braking force the pin 300 is actually unnecessary, although it may also be used, if desired.

When the pin 300 is provided, the user must, of course, be instructed to pull the pin 300 out before exerting his weight on the device since the pressure of the user's weight may make it difficult to withdraw the pin 300.

Since the walls 200 and 201 must be free to move toward each other, they are not directly and rigidly connected to the peripheral wall 213 but instead must be connected in such manner that they may have some movement toward and away from each other.

One means by which this function may be accomplished is to provide the walls 200 and 201 (Figure 6) with extensions 310 and recesses 311. The peripheral wall 213 is provided with extensions 315 which are bent over the side walls 200 and 201 at the recesses 311 between extensions 310, being so arranged that the walls 200 and 201 are free to move toward and away from each other.

In the foregoing the invention has been described solely in connection with specific illustrative embodiments thereof. Since many variations and modifications of the invention will now be obvious to those skilled in the art, it is preferred that the invention be bound not by the specific disclosures herein contained but only by the appended claims.

I claim:

1. An escape device comprising a reel, a casing therefor, said reel being rotatable in said casing; a flexible longitudinal member wound on said reel; an end of said flexible longitudinal member extending from said casing and providing means for securing to a relatively stationary support, a lever carried by said casing pivotally mounted therein; braking means carried by said

casing coacting with said reel; said braking means comprising a flexible brake band surrounding the periphery of said reel; said reel comprising a pair of circular guide plates defining a central area in which the longitudinal flexible member is wound; the peripheries of said guide plates having braking surfaces; said brake band engaging said braking surfaces, one end of said lever being connected to an end of said brake band; the other end of said brake band being held relatively stationary; the other end of said lever carrying a support for an individual; said lever operating said braking means in accordance with the weight of the individual.

2. An escape device comprising a reel, a casing therefor, said reel being rotatable in said casing; a flexible longitudinal member wound on said reel; an end of said flexible longitudinal member extending from said casing and providing means for securing to a relatively stationary support, a lever carried by said casing pivotally mounted therein; braking means carried by said casing coacting with said reel; said braking means comprising a flexible brake band surrounding the periphery of said reel; said reel comprising a pair of circular guide plates defining a central area in which the longitudinal flexible member is wound; the peripheries of said guide plates having braking surfaces; said brake band engaging said braking surfaces, one end of said lever being connected to an end of said brake band; the other end of said brake band being held relatively stationary; the other end of said lever carrying a support for an individual; said lever operating said braking means in accordance with the weight of the individual, said brake band having a slot permitting passage therethrough of the said extending portion of the flexible longitudinal member.

3. An escape device comprising a reel, a casing therefor, said reel being rotatable in said casing; a flexible longitudinal member wound on said reel; an end of said flexible longitudinal member extending from said casing and providing means for securing to a relatively stationary support, a lever carried by said casing pivotally mounted therein; braking means carried by said casing coacting with said reel; said braking means comprising a flexible brake band surrounding the periphery of said reel; said reel comprising a pair of circular guide plates defining a central area in which the longitudinal flexible member is wound; the peripheries of said guide plates having braking surfaces; said brake band engaging said braking surfaces, one end of said lever being connected to an end of said brake band; the other end of said brake band being held relatively stationary; the other end of said lever carrying a support for an individual; said lever operating said braking means in accordance with the weight of the individual.

5 weight of the individual, said brake band having a slot permitting passage therethrough of the said extending portion of the flexible longitudinal member; the means for holding the other end 10 of the brake band stationary comprising a second lever pivoted in said casing, the end of the lever on one side of the pivot being connected to the said other end of the brake band; the opposite end of the second lever riding on the outer turns of the flexible longitudinal member on the reel and varying the braking tension in accordance with the diameter of the unwound portion of the flexible longitudinal member.

4. An escape device comprising a reel, a casing therefor, said reel being rotatable in said casing; a flexible tape wound on said reel; an end of said flexible tape extending from said casing and providing means for securing to a relatively stationary support, a lever carried by said casing pivotally mounted therein; braking means carried by said casing coacting with said reel; said braking means comprising a flexible brake band surrounding the periphery of said reel; said reel comprising a pair of circular guide plates defining a central area in which the flexible tape is wound; the peripheries of said guide plates having braking surfaces; said brake band engaging said braking surfaces, one end of said lever being connected to an end of said brake band; the other end of said brake band being held relatively stationary; the other end of said lever carrying a support for an individual; said lever operating said braking means in accordance with the weight of the individual, said brake band having a slot permitting passage therethrough of the said extending portion of the flexible tape; the means for holding the other end of the brake band stationary comprising a second lever pivoted in said casing, the end of the lever on one side of the pivot being connected to the said other end of the brake band; the opposite end of the second lever riding on the outer turns of the flexible tape on the reel and varying the braking tension in accordance with the diameter 45 of the unwound portion of the flexible tape.
